UNITED STATES PATENT OFFICE.

JAMES A. McCLELLAN, OF MENOMONIE, WISCONSIN.

VICE ATTACHMENT.

1,249,148.

Specification of Letters Patent.

Patented Dec. 4, 1917.

Application filed November 15, 1916. Serial No. 131,527.

To all whom it may concern:

Be it known that I, JAMES A. McCLELLAN, a citizen of the United States, residing at Menomonie, in the county of Dunn and 5 State of Wisconsin, have invented a new and useful Vise Attachment, of which the following is a specification.

This invention has reference to attachments for vises. Owing to the curvature of 10 horseshoes, considerable difficulty has heretofore been encountered in rigidly holding the same between the jaws of the ordinary vise, commonly used in blacksmith shops, etc., for the reason that the said vise jaws, 15 in many instances, are too wide to enter between the side members of the shoe, in order to secure a good grip thereon.

The object of the invention is to provide a device capable of use in conjunction with 20 a vise of the ordinary construction, whereby horseshoes may be rigidly held, without damage to the shoe, during the operation of applying the calks or removing the same from the shoe.

25 Another object is to provide a shoe holding device, for attachment to a vise which will remain thereon, while in use, without the use of screws, clamps, or other fastening means, which will be automatically opened 30 and closed upon the proper manipulation of the vise, and which may be readily removed therefrom when the same is not in use.

A full and complete understanding of the 35 invention may be obtained from a consideration of the following detailed description, taken in connection with the accompanying drawing forming part of this specification; it being understood that while the drawing shows a practical form of the invention, the 40 latter is not confined to strict conformity therewith, but may be changed or modified, so long as such changes or modifications mark no material departure from the salient features of the invention, as specifically 45 pointed out in the claims appended hereto.

In the drawing, in which like reference numerals designate corresponding parts in each of the several figures:

Figure 1 is a perspective view of an ordinary vise showing the improved device applied thereto for holding a horseshoe.

Fig. 2 is a plan view on a larger scale showing the device in its normal or opened position.

55 Fig. 3 is a vertical sectional view, taken through the jaws of the vise and showing

the invention applied thereto and holding a horseshoe.

The invention comprises a pair of coacting jaws or clamping members 1 and 2, 60 which are adapted to be placed between the jaws of a vise 3 of any ordinary construction. The jaws or members 1 and 2 are similar, though not identical, in their construction, and are enlarged at one end to 65 provide relatively broad shoe-engaging portions which are adapted, when in use, to engage one side or the other of a horseshoe 4, and to rigidly hold the same in a horizontal position, upon the manipulation of the 70 vise 3, for the purpose of applying to or removing the calks 5 from the shoe 4, or for any other desired operation.

Each jaw is provided with an overhanging or offset enlargement or flange 6 and 7, 75 respectively, which are adapted to rest upon the top surface of the jaws of the vise 3, when the device is in use, to hold the same from downward movement. The coacting working faces of the jaws are provided with 80 arcuate seats or recesses 8 and 9, respectively, which are slightly undercut, as shown, to properly receive the tapering faces of one side of the horseshoe, and are correspondingly curved to properly fit the same 85 when the jaws of the device are closed upon the shoe to hold the same in position for operation.

The jaw or clamping member 1 is provided at its upper end with an arcuate recess 90 10 formed on a curve corresponding to the curvature of the horseshoe, and the opposite member 2 is provided with a correspondingly curved extension or supporting ledge 11, in spaced relation to the top face of the 95 member 2, and adapted to enter, or partly enter, the recess 10 when the device is in its active position, depending upon the width of the side of the shoe operated upon. A shelf 12 is thus provided by the extension 100 11, lying in a horizontal plane and spaced a sufficient distance from the top face of the clamping member 2 to permit the arm or side of the horseshoe to extend above the same, so that a wrench or other tool may be 105 readily applied to the polygonal portion of the calks 5, as in the horseshoes commonly used, for the purpose of removing the same, or otherwise operating upon them.

Each member 1 and 2 has corresponding 110 extensions or shanks 13 and 14 narrowing somewhat in width toward their free ends

and there provided with registering pintle ears 15 and 16, respectively, properly located to fit, one pair between the other, and perforated to receive the hinge pintle 17, for the purpose of hingedly connecting the two members together, and to permit their opening and closing as the same may be actuated by the manipulation of the vise 3. A coiled spring 18 is located upon the hinge pintle 17 in surrounding relation thereto and in the space 19 provided between the adjacent ears 16, said spring having its free ends 20 extending laterally of the pintle 17 a sufficient distance to engage the members 1 and 2, respectively. Recesses 21 are provided in the extensions or shanks 13 and 14 to receive the said ends 20 of the spring and to prevent the same from accidental displacement. A split key 22 is preferably provided to prevent the hinge pintle 17 from becoming displaced.

The ears 15 and 16 are offset sufficiently to permit the closing of the members 1 and 2 between the jaws of the vise, so that their opposed faces may be permitted to come in close relation to each other in the event of a very narrow shoe being operated upon.

The tendency of the coiled spring 18 is to open the jaws or members 1 and 2 and to cause the same to normally lie in alignment with each other as indicated in Fig. 2, so that it is necessary to manually close the jaws in order to introduce the same between the jaws of the vise 3, as indicated in Fig. 3, and it will be readily seen that the working members 1 and 2 will thus automatically open, as the actuating means of the vise 3 is operated to open the jaws of the latter. It follows that a shoe of any dimensions may be easily introduced between the jaws 1 and 2 in a position to rest upon the extension or ledge 11, and that, upon binding the same in the vise, the shoe will be rigidly held therein.

While I have shown and described my attachment as a holding vise for horseshoes, it will be obvious that by changing the shape of the seats or recesses 8 and 9, other devices having curved or irregular shapes could be held by the attachment, and I, therefore, do not wish to limit myself to an attachment for holding horseshoes.

What is claimed is:—

1. A holding attachment to be fitted between the jaws of a vise, comprising a pair of broad flat jaws hingedly connected at their lower ends and enlarged at their upper ends, and having at said upper ends seats provided on their inner faces and extending from one side to the other and open at their ends, said seats being undercut, and an inwardly extending horizontal shell be-

low the upper ends of said jaws and constituting the bottom for said seats, whereby a horse shoe may be placed and held in said seats and resting upon said shelf in a substantially horizontal position.

2. A holding attachment to be fitted between the jaws of a vise, comprising a pair of broad flat jaws hingedly connected at their lower ends and enlarged at their upper ends, and having formed thereon overhanging outer flanges to rest upon the jaws of the vise, and provided upon their inner opposed faces with arcuate seats which extend from one side to the other, and are open at their ends and are undercut, and an inwardly extending shelf on one of the jaws of the attachment at the bottom of said seats, said shelf being adapted to support a horseshoe arranged horizontally in the seats of the jaws, the depth of the seats being less than the thickness of the horseshoe so that the latter projects above the upper face of the jaws of the attachment.

3. A holding attachment for vises, comprising a pair of coacting jaws hingedly connected at one end, said jaws being provided with arcuate seats in their outer ends, and one jaw being formed below its seat with a recess and the other jaw having a supporting shelf registering with and projecting into the recess of the first-named jaw.

4. A holding attachment for vises, comprising a pair of coacting jaws hingedly connected at one end, a spring for normally opening the jaws, arcuate seats provided in the other ends of said jaws and adapted to register when the jaws are closed, a shoe-supporting shelf provided on one jaw below the seat thereon, and a corresponding recess provided in the other jaw and registering with the said shelf when the jaws are closed.

5. A device of the class described, comprising a pair of coacting jaws, arcuate shoe-receiving seats provided in said jaws adjacent to their ends and having undercut walls to conform to the walls of a horseshoe, an arcuate recess formed in one jaw adjacent to its shoe-receiving seat, a shoe-supporting shelf provided on the other jaw in alignment with the recess when the jaws are closed, shanks extending from the members and provided at their terminals with registering eyes, a hinge pintle connecting the eyes, and a spring mounted on the pintle to cause the jaws to normally open.

In testimony, that I claim the foregoing as my own, I have hereto affixed my signature in the presence of two witnesses.

JAMES A. McCLELLAN.
